[57] CLAIM

The ornamental design for a vibratory tumbler, substantially as shown.

DESCRIPTION

FIG. 1 is a perspective view of a vibratory tumbler showing my new design, the cord shown broken away to indicate indeterminate length;

FIG. 2 is an enlarged top plan view;

FIG. 3 is an enlarged right side elevational view;

FIG. 4 is an enlarged left side elevational view;

FIG. 5 is an enlarged bottom plan view thereof.
